UNITED STATES PATENT OFFICE.

ASHLEY GUY OGDEN, OF BALTIMORE, MARYLAND, ASSIGNOR TO MULTIPLE OFFSET MACHINE CO., OF BALTIMORE, MARYLAND, A CORPORATION OF MARYLAND.

PRINTING DEVICE.

1,244,362.

Specification of Letters Patent. Patented Oct. 23, 1917.

Application filed August 12, 1916. Serial No. 114,801.

To all whom it may concern:

Be it known that I, ASHLEY G. OGDEN, a citizen of the United States, and a resident of Baltimore, in the State of Maryland, have 5 invented certain new and useful Improvements in Printing Devices; and they consist in the constructions, combinations, and arrangement of parts hereinafter described and claimed.

10 My invention relates to printing devices for reproducing a multiplicity of prints arranged in symmetrical relation from a single negative.

A further object of my invention is to provide a device by means of which a sensitized plate may be moved with respect to the negative which is held in fixed position so that the design on the negative may be transferred to the plate a number of different 20 times; means being provided whereby the plate may be moved slightly from the negative in order to permit its movement relatively thereto into another position.

A further object of my invention is to provide a device of the type described, by means of which a sensitized printing plate may be quickly brought into position and may be stretched so as to prevent buckling of the plate.

30 A further object of my invention is to provide means whereby the negative may be centered before being placed in its final position in the printing apparatus, thereby facilitating the ease of operation of the latter.

A further object of my invention is to provide means which will raise the sensitized plate slightly to permit shifting of the same with respect to the negative, while 40 also permitting the plate to be swung back so as to permit access to the inside of the plate if desired.

Other objects and advantages will appear in the following specification, and the novel 45 features of the invention will be particularly pointed out in the appended claims.

My invention is illustrated in the accompanying drawings forming a part of this application, and in which:—

50 Figure 1 is a plan view of the device;

Fig. 2 is a front view of the device;

Fig. 3 is a side view of the device at right angles to Fig. 2;

Fig. 4 is a section through a portion of the device; certain parts being shown in 55 elevation;

Fig. 5 is a plan view of the frame which carries the sensitized plate;

Fig. 6 is an end view of the frame shown in Fig. 5; 60

Fig. 7 is a section on the line 7—7 of Fig. 5;

Fig. 8 is a section on the line 8—8 of Fig. 5;

Fig. 9 is a plan view of the bottom adjustable frame; 65

Fig. 10 is an end view of the frame shown in Fig. 9, certain parts being shown in section;

Fig. 11 is a section along the line 11—11 70 of Fig. 9;

Fig. 12 is a plan view of the top adjustable frame;

Fig. 13 is an end view of the frame shown in Fig. 12; 75

Fig. 14 is a section along the line 14—14 of Fig. 12;

Fig. 15 is a section along the line 15—15 of Fig. 12;

Fig. 16 is a plan view of a negative holder 80 plate and negative;

Fig. 17 is a section along the line 17—17 of Fig. 16; and

Figs. 18 and 19 are sections through a modified form of the sensitized plate retaining means. 85

In carrying out my invention, I provide a base or table 1 having suitable supports 2. This table is provided with a central circular opening 3. As will be seen from Fig. 90 1, the table has extensions 1^x and 2^x on opposite sides thereof. Run ways 4 which form a track are provided, this track extending over the table, and the extension as clearly shown in Fig. 1. 95

Referring now more particularly to Figs. 3 and 4 of the drawings, it will be observed that I have provided a pair of negative holders. These negative holders which consist of rectangular plates, as shown in Fig. 1, 100

are arranged to enter the run ways 4, so as to slide back and forth thereof. Each of the plates 5 has a circular portion 6 cut out on a bevel as shown at 6^x in Fig. 4. The circular plate 6 is adapted to rotate upon the body portion of the plate 5 in the same manner as a circular valve on its valve seat lubricating compounds being used to permit the plate 6 to be easily turned. Referring to Fig. 4, it will be seen that a plate of clear glass 7 is carried by the circular plate 6, this plate of clear glass being disposed above a rectangular opening 8, and projecting above the top of the plate 6. Arranged upon the plate of clear glass is a negative 9. The latter is held in position by means of a slideable clamping member 10, which may be adjusted so as to properly center the negative. From Fig. 4, it will be seen that this adjustable device 10 has an upturned flange which engages the negative but terminates short of the upper surface of the negative, thereby permitting the sensitized plate to be brought into intimate contact with the negative.

In Fig. 1, I have shown stop pins 11 disposed on the table 1, in such position that when one of the negative holders, *i. e.*, that on the left side of the machine is pushed in toward the center, it will engage the stop pins 11, thus bringing the negative exactly to the center of the machine. The table is provided with guide rails 12 at opposite edges thereof, these being V-shaped and arranged to receive V-shaped guide members 13^x of a movable frame 13. This frame 13 has V-shaped guide members 13^y (see Fig. 10) on its upper edges, these guide members being disposed at right angles to the guide members 13^x. Above the frame 13 is a frame 14, which has V-shaped grooves 14^x arranged to fit over the guide members 13^y so as to permit movement of the frame 14 transversely with respect to the frame 13.

The frame 13 is provided with pinions 13^p at the end of a common shaft 13^a (see Fig. 9), these pinions being arranged to engage racks 15 at the opposite edges of the table 1. The shaft 13^a bearing the pinions 13^p is provided at its end with a worm gear 16 which is driven by a worm 17, (see Fig. 2). This worm 17, it will be observed is feathered to a shaft 18, so as to slide longitudinally with respect to the shaft 18, but to turn with it. It is carried in a bracket 17^b, which extends downwardly from the frame 13. The handle 19 is secured to the end of the shaft 18 and is arranged to play over a dial 20 which is perforated so as to permit a portion of a spring pin 19^x carried by the handle, to enter. This forms a micrometer device for moving the frame 13 with respect to the table 1. Moreover it will be observed that as the handle 19 is turned,

in Fig. 2, the frame 13 will be moved in a direction parallel to the plane of the sheet.

Referring now to Fig. 10, it will be seen that the frame 14 is provided with a shaft 14^a, having at its ends pinions 14^p, which engage racks 21, carried by the movable frame 13. The shaft 14^a bears a worm wheel 22, which is feathered to it in a similar manner as the worm wheel 17 and which is carried between the brackets 22^x projecting from the frame 14. This worm wheel is engaged by a worm 23 on a shaft 24. This shaft 24 is provided with a handle 25 which plays over the dial 26, the arrangement constituting a micrometer device for moving the frame 14 transversely to the frame 13, and in a direction at right angles to the movement of the latter.

Secured to the frame 14 are upwardly extending brackets 27 through which extend shafts 28. These shafts are rotatable and are provided with cam portions 28^x (see Fig. 6) disposed in boxes 29^a, carried by the frame 29, which as will be observed from Fig. 6, is U-shaped so as to let it extend downwardly through the frames 13 and 14. From Fig. 6, it will be observed that the boxes 29^a on one side of the frame 29 are U-shaped so as to rest on the cams 28^x. The opposite boxes 29^b are rectangular for the purpose of providing hinges for the frame 29, as well as for raising it in a manner to be described later.

A handle 30 is disposed at the end of one of the shafts 28 (see Figs. 1 and 2) and this handle is connected by means of a link 31 with an arm 32, (see Fig. 2) on the shaft 28. This constitutes the means for rotating both of the shafts 28 simultaneously and to the same extent so that the cam members 28^x will be turned to raise the lower frame 29 bodily and the positions of the frame will always be parallel with one another. The frame 29 is provided with L-shaped sides (see Fig. 7), the bottom portion of one side having a series of upwardly extending pins 33. These pins are arranged to enter corresponding openings in the clamping device. See Fig. 7, which consists of a Z-shaped strip 34 and a straight strip 35, the sensitized plate 36 being disposed between the two and being held in position by means of the screws 37. The opposite edge of the sensitized plate 36 is held by the clamping device, which consists of an upper portion 38 and a lower portion 39, the upper portion being provided with brackets 40, holding screws 41, which extend through lugs 42 on the frame 29, winged nuts 43 being provided for moving the clamping device so as to tighten or stretch the sensitized plate and thereby prevent buckling.

Extending upwardly from the movable frames are uprights 44 (see Fig. 4). A

cross head 45 has a hinged connection 46 to one of the uprights, and has a removable pin 47 which extends through the other upright for holding the cross head in position. The 5 cross head bears a rock shaft 48 having arms 49, which are connected by links 50 to rock arms 51 on the shaft 52 bearing the cam 53. (See Fig. 4). The cam 53 is disposed in a recessed opening 54 of the frame 10 55 at the upper end of the plunger 56 so that when the rock arm 49 is moved by the handle 57 the cam 53 will be turned so as to raise or lower the plunger 56. The latter has an adjustable stem 58 which is secured 15 to a pressure head 59, guides 60 being provided for this head as shown in Fig. 4. The lower portion of the head is provided with a resilient covering 61.

When it is desired to raise the frame 29 20 which bears the sensitized plate 36 in order to inspect the plate, it may be done by turning a hand wheel 62, see Figs. 2 and 3. This hand wheel, it will be observed, is at the end of the shaft 63 which bears drums 25 64, flexible cables, 65, extend from the drums over the pulleys 66 carried on brackets 67, and are secured to eyes 68 carried by the frame 29. When the hand wheel is turned, the frame may therefore be raised on its 30 hinges. (See Fig. 6). It will be observed that the bracket 67 is inclined so as to permit the swinging of the frame 29 on its hinges.

Disposed below the table 1 is a lamp 68 which is carried by a post 69 preferably secured 35 to the table by posts 70. In Fig. 1, it will be seen that I have provided a screw 71 at the side of the table 1. This screw is used in connection with the pointer 72 carried by the frame 13, this pointer being capable 40 of being moved relatively to the frame to any desired position by a rotatable adjusting member 73. The frame 13 in turn carries a screw 74 which is used in connection with the pointer 75 of the frame 14. (See 45 Fig. 12).

From the foregoing description of the various parts of the device, the operation of the apparatus will be readily understood. The sensitized plate may be clamped between the clamping members 34 and 38, see 50 Figs. 7 and 8, prior to its positioning in the device. The cross head 45 may be raised by withdrawing the pin 47 and lifted outwardly on the handle 76 in any suitable 55 manner thereby lifting the pressure head out of the way. The sensitized plate may now be placed in position by slipping the member 34 over the pins 33, see Fig. 5, and tightening up on the nuts 43 so as to stretch 60 the plate and draw it into perfectly flat condition. The negative is placed in the circular portion 6 of the holder and is secured with registering indicating markers on the negative, and on the top of the body por-

tion of the holder, the circular portion of 65 the holder and the recessed portion may then be brought into proper position by means of registering marks near their edges. The squaring up of the negative may be easily facilitated by the use of a T-square 70 and triangle. The negative holder is now pushed inwardly until the edge of the portion 5 engages the stop pins, when the negative will be accurately centered.

The cross head now may be lowered and 75 the pin 47 be replaced. The position of the cross head may be adjusted by turning the threaded stem 58. The process is generally begun by making a print in one corner of the plate and when the negative is in proper 80 position, the handle 57 is then thrown downwardly thereby forcing the pressure head down upon the sensitized plate and bringing the latter into close contact with the negative. The electric light may be thrown 85 on, and the exposure made after which the light is turned out.

The handle 57 is now raised, thus relieving the pressure from the sensitized plate. The handle 30 is turned in the direction 90 shown by the arrow in Fig. 2 and thus lifts the frame 29 bearing the sensitized plate so that the latter is free from the negative. The handle 19 may now be used to move the frame 13 and also with it the frames 14 95 and 29 so as to bring the sensitized plate to another position with respect to the negative.

The greatest accuracy can be secured by the use of the screws and the micrometer 100 disks so that the accurate spacing of the designs which are to be duplicated on sensitized plates is assured.

Instead of printing on the sensitized metal plate, I may, if I desire, print on to another negative, and to this end, I provide a negative holder 80. This is used in connection with the pins 33 carried by the frame 29. To this end, the holder has a flange 80^x provided with holes 80^y arranged to slip over 105 the pins. The holder is provided with an opening which is covered by the negative 81. At 82 are recesses in the holder, in which are disposed wedges 83, the wedges having resilient material disposed next to the negative. By manipulating these wedges, the negative may be firmly clamped in position. The operation of the printing is similar to that already described in connection with the metal plate.

In Figs. 18 and 19 I have shown modified forms with means for holding the sensitized plate in position on the frame 29. (See Fig. 18). The hand clamp 85 is held by means of a screw 86 against the sensitized plate 36. In Fig. 19, the frame 29 has a Z shaped member 29^z between which and the support 87, the plate 36 is clamped, the set screw 88

holding the two clamping members firmly together.

In printing on the negative, it is advisable to use a cloth, such as that shown at 90 in Fig. 4 to prevent light getting to the parts of the plate not intended to be exposed.

The apparatus described provides means for quickly and economically printing large number of similar designs in a very short space of time, and absolutely spacing the designs symmetrically.

I claim:

1. In a printing device, a base provided with an opening, a stationary source of light disposed on one side of the opening, a negative carried by the base in registration with said opening, a frame movable in one direction with respect to said base, a second frame carried by said first named frame and movable thereon in a direction at right angles to the movement of the first named frame, a frame hinged to said second named movable frame and adapted to carry a sensitized plate, and means for exerting pressure on said sensitized plate to force the latter into contact with the negative.

2. In a printing device, a base provided with an opening, a stationary source of light disposed on one side of the opening, a negative carried by the base in registration with said opening, a frame movable in one direction with respect to said base, a second frame carried by said first named frame and movable thereon in a direction at right angles to the movement of the first named frame, a frame hinged to said second named movable frame and adapted to carry a sensitized plate, means for stretching said sensitized plate, and means for exerting pressure on the plate to bring the latter into engagement with the negative.

3. In a printing device, a base provided with an opening, a stationary source of light disposed on one side of the opening, a negative carried by the base in registration with said opening, a frame movable in one direction with respect to said base, a second frame carried by said first named frame and movable thereon in a direction at right angles to the movement of the first named frame, a frame hinged to said second named movable frame and adapted to carry a sensitized plate, and means for moving said hinged frame bodily in a direction normal to the plane of the negative while maintaining the plane of the sensitized plate parallel with the plane of the negative.

4. In a printing device, a base provided with an opening, a stationary source of light disposed on one side of the opening, a negative carried by the base in registration with said opening, a frame movable in one direction with respect to said base, a second frame carried by said first named frame and

movable thereon in a direction at right angles to the movement of the first named frame, a frame hinged to said second named movable frame and adapted to carry a sensitized plate, means for moving said hinged frame bodily in a direction normal to the plane of the negative while maintaining the plane of the sensitized plate parallel with the plane of the negative, said last means comprising a pair of shafts provided with cams and rectangular boxes carried by said hinged plate and arranged to be engaged simultaneously by said cams, and means for rotating said shaft simultaneously and to the same extent.

5. In a printing device, a base provided with an opening, a stationary source of light disposed on one side of the opening, a negative carried by the base in registration with said opening, a frame movable in one direction with respect to said base, a second frame carried by said first named frame and movable thereon in a direction at right angles to the movement of the first named frame, a frame hinged to said second named movable frame and adapted to carry a sensitized plate, means for moving said hinged frame bodily in a direction normal to the plane of the negative while maintaining the plane of the sensitized plate parallel with the plane of the negative, said last means comprising a pair of shafts provided with cams and rectangular boxes carried by said hinged plate and arranged to be engaged simultaneously by said cams, an arm connected with each of said shafts, and a link connecting said arms.

6. In a printing device, a base provided with an opening, a source of light disposed adjacent to said opening on one side thereof, a slid able negative holder carried by said base, guide means for guiding said negative holder to a position in registration with said opening, and means carried by said negative holder for centering the negative and for retaining it in its adjusted position.

7. In a printing device, a base provided with an opening, a source of light disposed adjacent to said opening on one side thereof, a slid able negative holder carried by said base, guide means for guiding said negative holder to a position in registration with said opening, and means carried by said negative holder for centering the negative and for retaining it in its adjusted position, said centering means consisting of a rotatable plate having a rectangular opening in its center and slid able clamps disposed on each side of said opening and arranged to engage the negative.

8. In a printing device, a base provided with an opening, a stationary source of light disposed on one side of the opening, a negative carried by the base in regis-

tion with said opening, a frame movable in one direction with respect to said base, a second frame carried by said first named frame and movable thereon in a direction 5 at right angles to the movement of the first named frame, a third frame carried by said second named movable frame, and movable toward and away from said negative, said third named frame being adapted to carry a sensitized plate, and means for exerting 10 pressure on said sensitized plate to force the latter into contact with the negative.

ASHLEY GUY OGDEN.
